US00D763340S

(12) **United States Design Patent**
O'Neill et al.

(10) **Patent No.:** US D763,340 S
(45) **Date of Patent:** ** Aug. 9, 2016

(54) **OPTICAL COMPONENT**

(71) Applicant: **olloclip, LLC**, Huntington Beach, CA (US)

(72) Inventors: **Patrick D. O'Neill**, Huntington Beach, CA (US); **Chong Pak**, Lakewood, CA (US); **Joshua Cantor**, Huntington Beach, CA (US); **Ryan Nguyen**, Fountain Valley, CA (US); **Jason Patrick**, Long Beach, CA (US); **Daniel Arato**, Los Angeles, CA (US)

(73) Assignee: **olloclip, LLC**, Huntington Beach, CA (US)

(**) Term: **14 Years**

(21) Appl. No.: **29/504,213**

(22) Filed: **Oct. 2, 2014**

(51) **LOC (10) Cl.** 16-06

(52) **U.S. Cl.**

USPC **D16/130**

(58) **Field of Classification Search**

USPC D10/78; D14/240, 251, 358, 432, 433; D16/130, 134, 136, 154, 208, 219; 92/161; 359/544, 808, 811, 818, 819, 359/823, 824, 826-828; 362/365; 396/529; 455/90.3, 556.1, 567, 569.1, 575.1, 455/575.8

CPC H04M 1/0264; G02B 7/14; G02B 7/02; G02B 13/001; G02B 13/003; G02B 13/005

See application file for complete search history.

(57) **CLAIM**

The ornamental design for an optical component, as shown and described.

DESCRIPTION

FIG. 1 is a front, top, and right side perspective view of an optical component;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines depict portions of the optical component that form no part of the claimed design.

1 Claim, 6 Drawing Sheets
